W. L. ECKHARDT

RADIO REPRODUCER

Filed July 9, 1926

UNITED STATES PATENT OFFICE.

WALTER L. ECKHARDT, OF PHILADELPHIA, PENNSYLVANIA.

RADIOREPRODUCER.

Application filed July 9, 1926. Serial No. 121,349.

My invention relates to sound reproducing devices comprising a diaphragm associated with a resonant unit and with means for effecting vibrations of the diaphragm in a manner to reproduce the modulations of the sound waves which have been impressed upon the vibratory member by which vibrations are imparted to the diaphragm.

My invention relates essentially to the diaphragm and it has for its general object to provide a diaphragm of novel construction including means whereby the modulations of the vibratory unit imposed thereon by the sound waves which are to be reproduced are accurately and faithfully reproduced.

It also is an object of the invention to provide a construction of radio reproducer including a vibratory diaphragm comprising a plurality of independently vibratable members, thereby affording means whereby an accurate reproduction of sound waves may be obtained.

Another object of the invention is to provide a diaphragm of a construction such that the extent or area of the diaphragm may be increased or diminished, as may be desired or required to meet conditions as they may arise in practice.

A further object of the invention is to provide a radio reproducer comprising a resonant member and a diaphragm respectively including means of novel character whereby they are adapted to cooperate to reproduce the finest and most delicate modulation of sound waves which may be imposed thereon.

To these and other ends my invention comprehends the construction and arrangement as hereinafter described in detail, particularly pointed out in the claims and as illustrated in the drawing in which I have shown one form of a convenient embodiment of the invention. However, it will be understood that the invention is susceptible of embodiment in other forms of construction than that shown and that changes in the details of construction may be made within the scope of the claims without departing from the invention.

In the drawing:

Fig. 1 is a view in front elevation of a radio reproducer embodying the invention, the closure of fabric or other material shown in Fig. 2 being omitted;

Fig. 2 is a vertical sectional view taken on the line 2-2 of Fig. 1; and

Fig. 3 is a sectional view through the central portion of the diaphragm with the parts enlarged so as to show more clearly the details of construction.

Referring to the drawing, 1 designates a base of relatively large dimensions and preferably of wood, upon which is mounted a shorter portion 2, also of wood, to which is secured a resonant member 3 of wood which is of drum or circular shape. The member 3 may be made up, as usual, of a number of thin sheets glued or otherwise secured together. One end of the member 3 may be closed by a wooden sheet 25 which constitutes a sounding board which cooperates with the diaphragm which will be hereinafter described. Mounted within the member 3 adjacent one end thereof and in proximity to the wooden sheet 25 is a rim 4 the inner edge of which is inclined downwardly, as indicated at 5. The diaphragm consists of a plurality of members 7 of suitable sheet material. These members are of the shape of isosceles triangles, as shown. They may consist of thin paper or parchment or other material of any character which may be found to be satisfactory. The members 7 may vary in thickness and stiffness and consequently in rigidity. It has been found that by employing a plurality of members in the construction of diaphragms for radio reproducers the said reproducers may be adapted for the receipt and reproduction of musical pieces varying in their characteristics; that is to say, a reproducer having a diaphragm of one construction has been found to be more satisfactory for the reception and reproduction of a certain musical piece than another reproducer containing another or different construction of diaphragm in which the members 7 were of different thickness or rigidity.

Also, by the employment of a diaphragm comprising a plurality of members, as illustrated, which overlap each other, as shown in Fig. 1 of the drawing, the area or amount of vibratory material may be varied.

In the securing of the members 7 to the resonant member 3 it will be noted that the corners of the triangular members at the bases thereof rest upon the inclined surface 5 of the rim 4 and that, in the construction shown, they are secured in place and held

thereto by means of a relatively narrow clamping rim 10. Obviously, the corners of the vibratory members 7 may be secured to the resonant member 3 in any other manner 5 which may be preferred or desired. Spaces of segmental shape are formed between the bases of the triangular members 7 and the opposing portions of the drum 3. The members 7 are inclined toward the opposite end 10 of the resonant member 3 and converge toward the axis thereof, as is clearly shown. The apical portions thereof overlap and are provided with openings 11 through which extends a binding member 12. One 15 end of the said member is provided with a head 13 and the opposite end thereof is screw-threaded for the reception of a binding nut 14. Preferably, the overlapped apical portions of the triangular members 20 7 are separated by washers 15, although such washers may be omitted if desired. Better results appear to be obtained when separating washers are employed.

It will be noted that the inner end portions of the triangular members 7 as they approach the axis of the resonant member 3 are bent reversely, as indicated at 16; that is, toward the plane of their connection to the resonant member 3, and then inwardly 25 or horizontally, as indicated at 17, in a direction substantially at right angles to the said axis.

It will be understood that the extent of lateral overlapping of the triangular members 30 7 may be varied and that if desired they need not be overlapped; also, that the edge dimensions of the said members may be varied; and that in consequence the area or extent of the vibratory medium or sheets 40 may be varied within wide limits.

The members 7 are independent of each other in consequence of which the thickness thereof may be varied; that is to say, certain 45 of the members may consist of sheet material of a certain thickness, while other members may consist of such material of a different thickness. By reason of the ability to vary the thickness of the sheets constituting the members 7 and to vary the extent 50 of overlapping of the said sheets great flexibility of construction is possible, thereby enabling the production of reproducers suited to the reproduction of musical or other sounds of different and varying characteristics.

For the purpose of effecting or causing vibratory movements of the members 7 of the diaphragm I have provided a loud speaker unit, indicated as a whole at 20, which may 55 be of any known construction, from the vibratory element of which extends a reed 21, the outer end of which passes through the axial hole 22 through the binding member 12 and is secured in place therein by means 60 of a binding screw 23. The loud speaker

unit is mounted upon the sounding board 25. Current for energizing the loud speaker unit 20 passes through the conductor 26.

The end of the resonant member 3 opposite the sounding board 25 may be closed by 70 means of a sheet of fabric or other suitable material 27 having a spring wire 28 in its outer edge which is adapted to fit within the interior of one end of the said member.

It will be seen that by my invention I have 75 provided a diaphragm of multiplex character whereby great flexibility of construction is obtained. Such variation may be effected by varying the length of the bases of the triangular members 7; by varying the thickness of the sheets of which the said members consist; and by varying the overlapping relationship of the said members to each other and thereby varying the area or extent of the vibratory element as a whole.

The sounds produced by the vibration of the sounding board 25 are allowed to pass freely past and beyond the diaphragm because of the presence of the spaces of segmental shape between the bases of the members 7 and the opposing portions of the drum 3.

Having thus described my invention, what I claim and desire to secure by Letters Patent is:

1. A radio reproducer comprising a diaphragm of multiplex character, the inner ends of the members of which are overlapped and secured together, and the outer portions of which are connected to a resonant member.

2. A radio reproducer comprising a diaphragm consisting of a plurality of sheets of material which converge toward a central point and the inner ends of which overlap each other and are secured together, and the outer portions of which are secured to a resonant member.

3. A radio reproducer comprising a diaphragm consisting of a plurality of triangular members of sheet material, which members converge toward a central point and the apical portions of which overlap each other at said central point, means for securing the said apical portions together, and the corners at the bases of said triangular members being mounted upon and connected to a resonant member.

4. A radio reproducer comprising, in combination, a resonant member of drum shape, a diaphragm consisting of a plurality of sheet members of triangular shape, each of which is connected at the corners of its base to the said resonant member, and the said triangular members extending inwardly and in a direction toward an end of the said resonant member, the inner end portions thereof being bent reversely and then extended horizontally into overlapping relationship 125 with respect to each other, means for secur-

ing the overlapped portions together, and means for connecting a loud speaker unit to the overlapped portions of the said diaphragm members.

5. A radio reproducer comprising a diaphragm consisting of a plurality of sheet members of isosceles triangular shape, which members are adapted to overlap each other and the corners of the respective members at 10 the opposite ends of the bases thereof being connected with and supported upon a resonant member, said members converging toward the axis of the said resonant member and also toward one end of said member, and 15 the apical portions thereof overlapping each other in line with the said axis, and means coincident with the said axis for fastening the said apical portions together.

6. A radio reproducer comprising a diaphragm of multiplex character, the inner 20 ends of the members of which are overlapped and secured together, said inner ends being separated by washers, and the outer portions of which members are connected to a resonant member.

7. A radio reproducer comprising a diaphragm consisting of a plurality of triangular members of sheet material, which members converge toward a central point and the 30 apical portions of which overlap each other at said central point, washers located between the overlapping apical portions, means for securing and binding the said apical portions and the said washers together, a resonant member comprising a portion 35 of drum shape, and means for securing the corners of the said members at the opposite ends of the bases thereof to the said drum shaped portion of the said resonant member.

8. In a radio reproducer, the combination 40 of a resonant member comprising a drum

shaped portion and a sounding board mounted thereon, a diaphragm comprising separate and independent members of sheet material 45 mounted at their outer ends upon the said drum shaped portion, said diaphragm comprising a plurality of independent members each of which subtends spaces between its outer end and the said drum shaped portion, 50 and the said members converging toward the axis of the said drum shaped member and overlapping each other in the line of said axis, and means for securing the overlapped portions together, substantially as described. 55

9. In a radio reproducer, the combination of a resonant member including a drum shaped portion and a sounding board closing one end thereof, a diaphragm mounted within said drum shaped portion, said diaphragm consisting of a plurality of triangular members, the corners of which at the opposite ends of the bases thereof are secured to the said drum shaped portion, and the said triangular members extending toward 60 the end of the said drum shaped portion opposite the said sounding board and converging toward the axis of the said drum shaped portion and overlapping each other in the line of said axis, and means for securing the 65 said overlapped portions together, substantially as described.

10. In a radio reproducer, the combination of a resonant member comprising a drum shaped portion and a sounding board mounted thereupon, and a diaphragm consisting of a plurality of separate members mounted upon the said drum shaped member and extending transversely thereof and in opposed 75 relation to the said sounding board. 80

In testimony that I claim the foregoing as my invention, I have hereunto signed my name this 2nd day of July, A. D., 1926.

WALTER L. ECKHARDT.
